[57] CLAIM

The ornamental design for a combined lint remover and shoe polisher, as shown and described.

DESCRIPTION

FIG. 1 is a perspective view showing one end, the top and one side of a combined lint remover and shoe polisher showing my design;

FIG. 2 is a perspective view showing the opposite end, opposite side and bottom of the combined lint remover and shoe polisher of FIG. 1;

FIG. 3 is an end view of the end of the combined lint remover and shoe polisher shown in FIG. 2;

FIG. 4 is a top plan view thereof, the bottom plan view being identical thereto.

FIG. 5 is a view similar to FIG. 1 of the combined lint remover and shoe polisher of FIG. 1 showing the upper lid removed;

FIG. 6 is a view similar to FIG. 1 of the combined lint remover and shoe polisher of FIG. 1 turned upside down and with the lower lid removed;

FIG. 7 is a perspective view of a second embodiment of a combination lint remover and shoe polisher.

FIG. 8 is an end view of the end of the variant of FIG. 7 shown in FIG. 7.

FIG.1

FIG. 3

FIG. 2

FIG. 4

FIG. 7

FIG. 8
